FLUID CONTROL

**Leland S. Hamer, Long Beach, Calif., assignor of
one-fourth to Paul A. Dewhirst, Los Angeles,
Calif.**

Application November 23, 1945, Serial No. 630,506

27 Claims. (Cl. 137—167)

1

This invention has to do with a fluid control and has particular reference to a device useful in a pipe line, or the like, to control flow therethrough, and is generally in the nature of a line blind. It is a general object of the present invention to provide a device of the character mentioned which is of simplified, improved and practical construction, making it useful in various situations where line blinds or the like are desired.

The device of the present invention is in the general nature of a pipe line fitting and is more specifically an angle type of fitting, that is, a fitting wherein there are sections that are tubular and which are angularly related relative to each other. The present invention contemplates an angle fitting wherein the sections are at any desired angle. However, as a typical example of the invention I will describe it as a right angle fitting, that is, a fitting wherein the sections are at right angles to each other and, further, the particular fitting that I have shown is in the nature of a T.

A general object of my invention is to provide a fitting of the general character referred to having an improved operating means whereby I gain a very effective closing or clamping action through a very simple, easy operation. The structure that I have provided involves, generally, a differential operating means or a thread device involving differential thread means, and when the device is operated the clamping member is operated slowly but with great force.

Another object of the present invention is to provide a fitting of the general character referred to which has a catch chamber at the point where the control or blinding plate is carried, so that fluid is not spilled from the fitting in the course of changing or manipulating the plate.

Another object of my present invention is to provide a fitting of the general character referred to wherein there is a clamp member that engages the plate to clamp it against a seat, which clamp member is effectively guided by the means through which it is operated. By guiding the clamp member I eliminate danger of the parts becoming misaligned and binding in the course of operating the device.

Another object of my present invention is to provide a fitting of the general character referred to involving an operating means for the plate clamp which means is located entirely at the exterior of the body or free of the fluid passages so that flow of fluid is in no way impeded or interfered with.

2

Another object of my present invention is to provide a fitting of the general character referred to in which the operating force is generated by or from a single screw member and is communicated to the plate clamping member so that it is operated positively and uniformly and with a minimum of structural deflection. In the construction that I have provided I employ a plurality of tie rods that extend to and operate the member that clamps the plate and the tie rods are symmetrically arranged around the axis of the plate clamp and they are located immediately adjacent the exterior of the body section to which the plate is clamped, so that they exert force to the clamping member at points close to its central axis.

The various objects and features of my invention will be fully understood from the following detailed description of typical preferred forms and applications of the invention, throughout which description reference is made to the accompanying drawings, in which:

Fig. 1 is a plan view of a pipe line fitting embodying the construction that I have provided, the particular fitting shown being a T fitting. Fig. 2 is an end view of the device shown in Fig. 1, being a view taken as indicated by line 2—2 on Fig. 1. Fig. 3 is an enlarged longitudinal sectional view of the device, being a view taken as indicated by line 3—3 on Fig. 1. Fig. 4 is an enlarged detailed sectional view of a portion of the structure shown in Fig. 1, being a view taken as indicated by line 4—4 on Fig. 1. Fig. 5 is a transverse sectional view of the structure, being a view taken as indicated by line 5—5 on Fig. 3. Fig. 6 is a transverse sectional view of the structure, being a view taken as indicated by line 6—6 on Fig. 3. Fig. 7 is a detailed view illustrating the differential screw mechanism that I have provided; parts of the mechanism being broken away to show in section. Fig. 8 is an enlarged detailed sectional view showing the manner in which the plate is sealed with the body and clamp member. Fig. 9 is a view similar to Fig. 8 showing a modified form of construction, and Fig. 10 is a view similar to Fig. 4, showing a modified form of construction.

The device illustrated throughout the drawings as a typical embodiment of my invention is an angle fitting in the nature of a T, that is, a fitting wherein there is a body having a transverse tubular section A and what I will term a longitudinal tubular section B. I am referring to the section B as longitudinal since it extends in the direction of the central axis of the mechanism that I have provided. In accordance with

the broader aspects of my invention the fitting may be in the nature of an L as distinguished from a T, in which case the section A which is referred to as transverse, is open at one end only. In the preferred form of the invention the body sections A and B are cast or otherwise suitably formed integrally or as a unit, and where the body is to be connected with or to other parts, such as to pipe sections, it is provided with suitable coupling means. In the particular form of the invention illustrated the body section A is provided at its ends with coupling flanges 10 while the body section B is without a coupling flange, since it does not connect directly to another part or pipe line, but rather carries the clamp member which, in turn, is provided with a coupling flange, as I will hereinafter describe.

The construction that I have provided involves, in addition to the body having sections A and B, a flow control plate C, a clamp member D operable to clamp the plate against a seat provided at or on the body B sealing means E at the plate to prevent leakage of fluid at the plate, an operating mechanism F and connecting means G between the operating mechanism and the clamp member.

In the preferred form of my present invention the plate receiving seat is formed on or by the body section B. In fact, it is preferably formed at or by the outer end 11 of the body section B, which end is normal to the longitudinal axis of the section B or to the fluid passage 12 through the section B.

The control plate C may be any suitable blind or control plate, such as is used in line blinds or the like. As an example of a control plate I have shown one having two ends, one a closed end 14 and the other an open end 15, the open end being provided with a bore or aperture 16 for passing fluid. In practice the bore 16 of the control plate may be of any desired size relative to the flow passage provided in the body of the fitting. In the particular case illustrated I have shown an aperture 16 in the plate part 15 corresponding in size to the bore 12 of section B of the body.

The clamp member D that I have provided is carried by the outer or projecting end portion of the body section B and when in place it forms or may be considered a part or extension of the body section, although it is operable to move relative to the portion of the body section B that is joined to the body section A. The clamp member in its preferred form is a collar-like element with a collar portion 20 provided at its inner end with a clamp face 21 facing or opposing the seat 11 and provided at its outer end with coupling means for making connection to a pipe section, or the like. In the particular form of the invention illustrated I have shown a coupling flange 22 provided on the outer end of the collar part 20.

In accordance with my invention I provide or form the clamp member with an enlargement or housing 25 which surrounds the clamp face 21 and projects from the inner end of the collar 20 to overlap the projecting outer end of the body section B. In the preferred construction the exterior 26 of the outer end portion of the body section B is turned and slidably fits into a bore 27 provided in the enlargement or housing portion 25 of the clamp member so that the projecting end of the section B projects into the housing. The housing is completely enclosed except at one side where it has a lateral side opening 30 which is wide enough to admit the plate C. The plate

10 C when in operating position projects into the housing of the clamp member and has one end located between the seat 11 of the section B and the clamp face 21 of the clamp member D. When the clamp member is formed with a housing 25 having a single lateral or side opening 30 the fitting can be used so that the opening faces upward, in which case the housing forms a catcher or receptacle for fluid that might otherwise flow or drain from the fitting when the plate is being changed or operated. It is to be understood, of course, that the housing 25 will not retain fluid if there is a head pressure on the fitting, but will only hold fluid if there is fluid standing in the line without being under pressure.

15 The sealing means E provided between the plate and the seat 11 or the clamp face 21, or both, may vary depending upon the working conditions or the type of fluid being handled and in practice I may use any suitable or appropriate form or type of packing. In Figs. 3 and 8 of the drawings I show a construction wherein both sides of the plate at both portions thereof are plain and smooth, while the seat has a channel 25 35 formed therein carrying a packing ring 36 and the clamp face has a channel 37 formed therein carrying a packing ring 38. The packing rings 36 and 38 project from the seat and face, respectively, to have sealing engagement with the plate, as shown in the drawings.

20 In the modified form of construction illustrated in Fig. 9 the seat 11a is plain and smooth and the clamp face 21a is plain and smooth, but the plate C has a channel 35a formed therein carrying a packing ring 36a to engage the seat 11a while the other side of the plate has a channel 37a formed therein carrying a packing ring 38a to engage the clamp face 21a.

25 In the preferred form of my invention I provide packing means or a sealing ring 40 between the housing portion 25 of the clamp member and the projecting end of the body section B. In the particular case illustrated in the drawings the packing ring 40 is carried in a channel 41 provided in the wall of the bore provided in the housing 25 to receive the turned end portion 26 of the body section B.

30 The operating means F that I have provided preferably involves a single manual control or operating member 45 and a screw means or differential screw mechanism by which I gain a substantial mechanical advantage or leverage. The preferred form of mechanism as shown in the drawings involves, generally, a head 46 which 35 I will refer to as an outer member, a stud 47 which I will refer to as an inner member, and a single rotatable screw member 48 engaging and operating between the head and stud. The head 46 is a movable or shiftable part to which the connecting means G is attached through lugs 43 of the head. I may strengthen the lugs 43 by means of ribs 44 and I support the head 46 so that it is guided for movement in the desired direction. In the particular construction shown a projection 49 is provided on the body and has its outer 40 surface 50 turned concentric with the axis of the mechanism that I am describing, which axis is concentric with that of the opening 12 in section B and the opening 12a in the clamp member, which registers with and is the same size as the opening 12. The operating member 45 is secured to the screw member 48 by action of the screw threads 45a on the operating member engaging with the screw threads 48a on the screw member. 45 The operating member and the screw member

are held against rotation relative to each other by means of screws 72^a which key these two elements together and further secure a plug 72 which I will hereinafter describe. The head 46 has a bore or socket 51 entering it from its inner end, which socket slidably receives the outer surface 50 of the projection 49.

The stud 47 is a stationary or fixed element projecting outward from the projecting part 49 and arranged concentric with the mechanism that I am describing. The screw member 48 connects the head 46 and stud 47 by being externally threaded and screwed into a central bore 55 provided in the head and by being internally threaded and screwed onto the stud 47. The threads 56 on the outside of the screw member 48 are pitched in the same direction as the threads 57 on the inside of the screw member. However, they differ in number, that is, there is a different number of threads 56 than there are threads 57 for a given length of the screw member. For example, in practice I may provide about 11 threads per inch on the inside of the screw member 48 and 10 threads per inch on the outside of the screw member 48.

The stud 47 may be fixed on or made to project from the projection 49 in any suitable manner. In the case illustrated I have shown the stud formed separately from the projection and have shown the screw threaded into an opening in the projection and a transverse pin 47^a fixes the stud against displacement from the projection.

The operating member or hand wheel 45 is directly connected to the screw member 48 to turn it and in the preferred construction a protective shield 60 is provided on the hand wheel to slidably extend over the projecting turned outer end portion 61 of the head 46. The sleeve 60 is made long enough so that it is maintained over the part 61 of the head 46 throughout operation of the mechanism. In practice it is desirable to maintain a lubricant in the screw mechanism that I have just described and it is preferred to construct the mechanism so that foreign matter is kept out of the screw mechanism. In the particular case illustrated a sealing ring 70 is arranged between the turned part 50 of the projection 49 and the bore 51 of the head and a sealing ring 71 is provided between the projecting part 61 of the head and the protective sleeve 60 of the hand wheel. A plug or closure 72 is provided to close the outer end of the tubular screw member 48 and a suitable grease fitting or connection 73 is provided so that a suitable lubricant can be introduced into the screw mechanism. Passages 74 may be provided to facilitate the flow of lubricant to the moving parts.

The connecting means G that I have provided may vary considerably in construction and formation. Broadly, the connecting means acts as a tie between the head 46 of the operating mechanism and the clamp member D which engages the plate C. In the preferred form of my invention the connecting means G is located or arranged entirely at the exterior of the body so that there are no parts whatever projecting into the fluid passages established by the body sections A and B. In the form of invention shown in Figs. 1 to 7, inclusive, the connecting means involves a plurality of tie rods 75 to extend between the lugs 43 of the head 46 and the clamp member D. In the construction illustrated there are four studs 75 and these studs are equally spaced around the axis of the operating mech-

anism F and are equidistant from the axis of the mechanism F. In accordance with my invention I connect the rods 75 to the clamp member D so that they do not reach or intersect the plane of operation of the plate C. In the construction illustrated bosses 76 project from the inner end portion of the clamp member D or from the housing 25 toward the head 46. The bosses have tapped openings 77 and the tie rods have reduced threaded end portions 78 which are threaded into the opening 77 so that the ends 79 of the tie rods seat against the outer ends 80 of the bosses. Through this construction the rods are effectively connected to the bosses in a predetermined position and project rigidly therefrom toward the head 46. The head 46 has lugs 43 strengthened by the ribs 44 and has openings 90 passing the reduced end portions 91 of the tie rods 75 so that the ends 92 of the tie rods seat against the surfaces 93 of the lugs 43. The reduced end portions 91 of the tie rods are threaded and extend beyond the lugs 43 sufficiently to carry the nuts 94. In practice the tie rods may be bolt-like members having ends 79 and 92 which properly space the clamping means D from the head 46.

The guide lugs 81 project from the body section A and in practice are part of and are integral with the body section. The tie rods 75 slidably pass through the openings 82 in the guide lugs 30 to engage the head 46. Through the mechanism just described the clamping means D is held rigidly against rotation relative to body sections A and B and the mechanism F.

In the form of the invention illustrated in Fig. 35 10 of the drawings I provide for adjusting the clamp member D relative to the head 46. In this form of construction the tie rods 75^a may be connected to the clamp member D by threading into the bosses 76^a and slidably pass through 40 the guide lugs 81^a on the body section A. The lugs 43^a of the head 46 have openings 90^a passing the threaded end portions 91^a of the end portions 91^a to adjustably connect the head 46 to the clamping means D. Through this construction the tie rod 75^a and the nuts 94^a and 95^a can be adjusted to vary the spacing of the clamp member from the head and any inequality or misalignment can be compensated for through suitable manipulation of the nuts on the tie rods.

In operating the mechanism that I have provided, assuming the clamping member D to be released or backed away from its clamping position, the desired end of the plate C is arranged 55 between the seat 11 and the clamp face 21, the operating member 45 is then turned in a direction so that the threaded engagement between the screw 48 and the head 46 causes the head to be moved out or in the direction indicated by the arrow in Fig. 3. When the screw member is turned in this direction the screw member is bodily advanced inward or toward the body because of its being threaded onto the fixed stud 47. The difference in number of threads, as 60 above described, results in a differential movement or action so that the actual movement of the head 46 relative to the body of the fitting is very slight and, consequently, there is a very great mechanical advantage set up between the operating member 45 and the head 46. As the head 46 moves in the direction indicated by the arrow in Fig. 3 the clamp member D through the connecting means G moves toward the body section B so the clamp face 21 bears toward the 65 plate C and clamps the plate on the seat 11. The

sealing means **E** provided in the clamp plate assures a tight connection so that there is no leakage around the plate and the differential mechanism makes it possible to clamp the plate **C** with great force so that the fitting will withstand very high pressures. To change the plate **C** or to reverse its position it is merely necessary to move the operating member **45** in the opposite direction, causing the head **46** to move in the opposite direction or toward the body of the fitting with the result that the clamp member **D** is pushed away from the plate **C**, releasing the plate so that it is free to be handled as desired. If the fitting is installed as above described, the housing **25** catches any fluid that would otherwise spill when the clamp member **D** is released, assuming, of course, that there is no head pressure on the fitting.

Having described only typical preferred forms and applications of my invention, I do not wish to be limited or restricted to the specific details herein set forth, but wish to reserve to myself any variations or modifications that may appear to those skilled in the art and fall within the scope of the following claim.

Having described my invention, I claim:

1. In a device of the character described, a rigid body with an elongate portion having a flow passage therein and with a laterally projecting portion at one side of the elongate portion and having a flow handling duct in communication with the passage, the projecting portion having an annular seat concentric with the duct, a flow controlling plate having sealing engagement with the seat, and means operating the plate relative to the seat including, a single rotatable element at the opposite side of the elongate portion of the body and having concentric differential threads, the body having a part connected therewith and engaged by one of the threads and means cooperating with the other of said threads and associated with said plate to effect said sealing engagement between said plate and said seat.

2. In a device of the character described, a body having a flow passage, a closure engaging the body to control flow through the passage, and means operating the closure relative to the body including, a manually operated operating member and differential screw means acting between the operating member and the closure, the screw means including, an externally threaded part rigid on the body, an internally threaded part coupled with the closure and communicating force thereto, and a rotating screw member having threads of different pitch engaged on the first mentioned part and in the other part.

3. In a device of the character described, a body having a flow passage, a closure engaging the body to control flow through the passage, and means operating the closure relative to the body including, a manually operated operating member and differential screw means acting between the operating member and the closure, the screw means including, an externally threaded part fixed on the body, an internally threaded part coupled with the closure and communicating force to the closure, and a rotating screw member threaded onto the first mentioned part and into the other part, the threads of said parts being pitched in the same direction and differing in number so the said other part is moved to operate the closure when the screw member is rotated.

4. In a device of the character described, a

body having a flow passage, a closure engaging the body to control flow through the passage, and means operating the closure relative to the body including, an operating member and differential screw means acting between the operating member and the closure, said means including, an externally threaded fixed stud projecting from the body, an internally threaded head concentric with the stud and coupled with the closure to communicate force thereto, and a screw member threaded onto the stud and into the head, the threads of the stud and head being different.

5. In a device of the character described, a body having a flow passage, a closure engaging the body to control flow through the passage, and means operating the closure relative to the body including, an operating member and differential screw means acting between the operating member and the closure, the screw means including, two parts one internally threaded and the other externally threaded, and a screw member having threaded engagement with the two parts, one of the parts being fixed to the body and the other being movable relative to the body and coupled to the closure to shift it relative to the body, the threads of said parts being of different pitch.

6. In a device of the character described, a body having a flow passage, a closure engaging the body to control flow through the passage, and means operating the closure relative to the body including, an operating member and differential screw means acting between the operating member and the closure, the screw means including, two parts one internally threaded and the other externally threaded, the threads of said parts being of different pitch, a screw member having threaded engagement with the two parts, one of the parts being fixed relative to the body and the other movable relative to the body and coupled with the closure to shift it relative to the body, and means guiding the movable part relative to the body.

7. In a device of the character described, a body having a flow passage, a closure engaging the body to control flow through the passage, and means operating the closure relative to the body including, an operating member and differential screw means acting between the operating member and the closure, the screw means including, two parts with differently pitched threads, the threads of one of the parts being internal, a screw member having threaded engagement with the two parts, one of the parts being fixed relative to the body and the other movable relative to the body and operating the closure, and means sealing the threaded portions of said parts against foreign matter from the exterior of the device.

8. In a device of the character described, a body having a flow passage, a closure engaging the body to control flow through the passage, and means operating the closure relative to the body including, an operating member and differential screw means acting between the operating member and the closure, the screw means including, an externally threaded fixed stud projecting from the body, an internally threaded head, means coupling the head with the closure, a screw member threaded onto the stud and into the head and carrying the operating member and rotatable to move the head relative to the body, sealing means between the head and body, and sealing means between the operating member and head.

9. In a device of the character described, a body having a flow passage and a projecting guide part, a closure engaging the body to control flow through the passage, and means operating the closure relative to the body including, an operating member and differential screw means acting between the operating member and the closure, the screw means including, an externally threaded fixed stud projecting from the body, an internally threaded head shiftable relative to the body and operatively coupled with the closure, and a screw member threaded onto the stud and into the head, the head having an opening slidably receiving the guide part projecting from the body.

10. In a device of the character described, a body having a flow passage and an external guide projection, a closure engaging the body to control flow through the passage, and means operating the closure relative to the body including, an operating member and differential screw means acting between the operating member and the closure, the screw means including, an externally threaded fixed stud projecting from the body, an internally threaded head shiftable relative to the body and operatively coupled with the closure, and a screw member threaded onto the stud and into the head, the head having an opening slidably receiving the guide projecting from the body, the operating member being carried by the screw member and having a part slidably engaging the head.

11. In a device of the character described, a rigid body with an elongate portion having a flow passage therein and with a laterally projecting portion at one side of the elongate portion and having a flow handling duct in communication with the passage, the projecting portion having an annular seat concentric with the duct, a flow controlling plate having sealing engagement with the seat, and means operating the plate relative to the seat including, a rotatable operating member at the exterior of the elongate portion and at the opposite side thereof, a unit shiftable relative to the body and confined to the exterior thereof and having a head at the said opposite side of the elongate portion and a plurality of rigid rods extending from the head to the plate, and a screw operated by the operating member and having differential threads, one of the threads being engaged with the head, and a part on the body engaged by the other thread.

12. In a device of the character described, a rigid body with an elongate portion having a flow passage therein and with a laterally projecting portion at one side of the elongate portion and having a flow handling duct in communication with the passage, the projecting portion having an annular seat concentric with the duct, a flow controlling plate having sealing engagement with the seat, an annular clamp engaging the plate and holding it against the seat, and means operating the plate relative to the seat including, a rotatable operating member at the exterior of the elongate portion and at the opposite side thereof, a unit shiftable relative to the body and confined to the exterior thereof and having a head at the said opposite side of the elongate portion and a plurality of rigid rods extending from the head to the clamp, and a screw operated by the operating member and having differential threads, one of the threads being engaged with the head, and a part on the body engaged by the other thread.

13. In a device of the character described, a

body having a flow passage, a plate engaging the body to control flow through the passage, an operating member, a screw means operated by said member, and means operating the plate from the said screw means including a plurality of tie members operated simultaneously by the screw means and guides on the body slidably supporting and guiding the tie members from the body.

14. In a device of the character described, a body having a flow passage therethrough and having a seat at one end of the passage and a wall spaced from the seat and intersecting the axis of the seat, a plate engaging the seat and controlling flow through the passage, an operating member, a screw means operated by said member and supported by and at the exterior of said body wall, and means operating the plate from the said screw means and into engagement with the seat including, a clamp member opposing the seat and engaging the plate and a plurality of spaced parallel tie members connected with the clamp member and operated simultaneously by the screw means to move the clamp member toward the seat and clamp the plate thereto.

15. In a device of the character described, a rigid body with an elongate portion having a flow passage therein and with a laterally projecting portion at one side of the elongate portion and having a flow handling duct in communication with the passage, the projecting portion having an annular seat concentric with the duct, a flow controlling plate having sealing engagement with the seat, an annular clamp engaging the plate and holding it against the seat, and means operating the plate relative to the seat including, a rotatable operating member at the exterior of the elongate portion and at the opposite side thereof, the axis of rotation of said member being coincident with the longitudinal axis of the duct, a unit shiftable relative to the body and confined to the exterior thereof and having a head at the said opposite side of the elongate portion and a plurality of rigid spaced parallel rods extending from the head to the plate and parallel with the longitudinal axis of the duct, and a screw concentric with and operated by the operating member and having differential threads, one of the threads being engaged with the head, and a part on the body engaged by the other thread.

16. In a device of the character described, a body having a flow passage and a seat around the passage, a plate engaging the seat, a clamp member engaging the plate operable to clamp it to the seat, the clamp member having a housing portion with a side opening admitting the plate to position to engage the seat, an operating member, a screw means operated by said member, and a plurality of spaced rods acting under tension connecting the screw means and clamp member.

17. In a device of the character described, a body having a flow passage and a seat around the passage, a plate engaging the seat, a clamp member engaging the plate and operable to clamp the plate to the seat, the clamp member having a housing portion with an opening slidably receiving the body and a side opening admitting the plate to position to engage the seat, an operating member, a screw means operated by said member, and rods operatively connecting the screw means and the clamp member.

18. In a device of the character described, a body having a flow passage and a seat at one end and around the passage, a plate engaging the

seat, a clamp member engaging the plate operable to clamp it to the seat, the clamp member having a housing portion with an opening slidably receiving the said end of the body and a side opening admitting the plate to position to engage the seat, an operating member, a screw means operated by said member, and tension rods connecting the screw means and the clamp member.

19. In a device of the character described, a body having a flow passage and a seat around the passage, a plate engaging the seat, a clamp member engaging the plate operable to clamp it to the seat, an operating member, a screw means operated by said member, rods connecting the screw means and clamp member, and guide means on the body slidably supporting the rods.

20. In a device of the character described, a body having a flow passage and an outwardly facing seat at one end of the passage, a plate engaging the seat, a clamp member having a part outward of the said end of the body engaging the outer side of the plate to clamp the plate to the seat and having a part inward of the said end of the body having sliding engagement with the body, and means operating the clamp member including spaced parallel operating rods at the exterior of the body and connected to the last mentioned part of the clamp member.

21. In a device of the character described, a body having a flow passage and an outwardly facing seat at one end of the passage, a plate engaging the seat, a clamp member having a part outward of the said end of the body engaging the outer side of the plate to clamp the plate to the seat and having a part inward of the said end of the body having sliding engagement with the body, and means operating the clamp member including spaced parallel operating rods immediately adjacent the exterior of the body and connected to the last mentioned part of the clamp member, and a single means acting to simultaneously move the rods.

22. In a device of the character described, a body having a flow passage and an external seat at one end of the passage, a plate with its inner side engaging the seat, a clamp member having a part engaging the outer side of the plate to clamp the plate to the seat and having an inner part slidably engaging the body, and means operating the clamp member including spaced operating rods at the exterior of the body acting under tension and connected to the last mentioned part of the clamp member, and a single screw means at the exterior of the body simultaneously operating the rods.

23. In a device of the character described, a body having a flow passage and a seat around the passage at one end of the body, a plate engaging the seat, a clamp member having a part outward of the said end of the body engaging the plate to clamp it to the seat and having a part inward of the said end of the body slidably engaging the body, and means operating the clamp member including spaced parallel operating rods at the exterior of the body and connected to the

last mentioned part of the clamp member, and a single differential screw means at the exterior of the body operating the rods.

24. In a device of the character described, a body having a flow passage and a seat around the passage at one end of the body, a plate engaging the seat, a clamp member having a part outward of the said end of the body engaging the plate to clamp it to the seat and having a part inward of the said end of the body slidably engaging the body, and means operating the clamp member including spaced operating rods operating under tension at the exterior of the body and connected to the last mentioned part of the clamp member, and a single screw means operating the rods and including a head operated by a screw and carrying the rods to operate them.

25. In a device of the character described, a body having a flow passage and a seat at one end, a plate engaging the seat, a clamp member having a part outward of the said end of the body engaging the plate to clamp it to the seat and having a part inward of the said end of the body, and means operating the clamp member including spaced operating rods at the exterior of the body and connected to the last mentioned part of the clamp member, and a single screw means operating the rods and including, a screw, a head operated by the screw, and means connecting each of the rods to the head for adjustment relative thereto.

26. In a device of the character described, a body having two angularly related tubular sections, one a longitudinal section having a seat at its outer end portion and a wall at its inner end transverse of the axis of the seat, a plate engaging the seat, and means clamping the plate to the seat including, a clamp member engaging the plate, screw means at the exterior of the body and carried by the said wall of the body, and spaced members at the exterior of the body connecting the screw means and clamp member.

27. In a device of the character described, a body having two angularly related tubular sections, one a longitudinal section having a seat at its outer end portion, a plate engaging the seat, and means clamping the plate to the seat including, a clamp member engaging the plate, screw means at the exterior of the body beyond the other end of the body, and spaced members at the exterior of the body connecting the screw means and clamp member, the said spaced members being symmetrically arranged around and equally spaced from the axis of the screw means and having sliding engagement with the body.

LELAND S. HAMER.
